FIG. 5

H. Sabrowske

By *John Dunstan*,
his Attorney

UNITED STATES PATENT OFFICE.

HERMAN SABROWSKE, OF ELYRIA, OHIO.

CAR REPLACER.

Application filed March 20, 1923. Serial No. 626,302.

To all whom it may concern:

Be it known that I, HERMAN SABROWSKE, a citizen of the United States, residing at Elyria, in the county of Lorain and State 5 of Ohio, have invented certain new and useful Improvements in Car Replacers, of which the following is a specification.

This invention relates to car replacers, and has for its principal object to provide 10 car replacers of such construction that the inside and outside derailed wheels of a car will be gradually elevated and guided smoothly upon the rails thereby necessitating but a minimum of power applied to the 15 car and eliminating the usual jolting thereof.

Another object of the invention is to provide car replacers of simple and practical construction, which are easily and securely 20 fixed to the sides of the rails at a desired position for efficiently guiding the derailed wheels of a car upon the rails.

With the above and other objects in view, the invention will be hereinafter fully 25 described as illustrated in the accompanying drawings, and the novel features thereof will be distinctly pointed out in the appended claims.

In the drawings similar characters of reference are used to designate corresponding parts.

Figure 1 is a plan view of car replacers constructed in accordance with my invention and applied to the rails of a track.

Fig. 2 is a side elevation of the inside car replacer.

Fig. 3 is a similar view of the outside car replacer.

Fig. 4 is an end view of Fig. 2.

Fig. 5 is an end view of Fig. 3, and

Fig. 6 is a cross-sectional view illustrating the means for securing the car replacer to the rail.

Referring to the drawings, 1 represents 45 the replacer for applying to the inside of a rail 2, and 3 the replacer for applying to the outside of the rail 4. Said rails rest upon and are fixed to the cross-ties indicated by 5. The inside replacer 1 consists of an 50 elongated body having a base 6 adapted to rest upon a pair of the cross-ties 5, and said base is cut off or inclined at 7 to fit over and rest upon the upper side of the base of the rail. Said elongated body has inclined 55 upper surfaces 8 and 9 extending gradually

upwardly from each end thereof to its transverse center and highest point 10. The inner side of the body 1 is cut down to provide a longitudinal strip 11 which is provided with end facing lugs 12 and 13 adapted to engage the web of the rail, and from the upper surface 14 of said strip to the highest point 10 of said body and rounding into the inclined surfaces 8 and 9 thereof, the surface is convex as indicated at 15. 60 The body 1 is of greater width at each end and decreases from the outer side thereof toward its transverse center which is curved longitudinally at 16, and formed integrally upon the top edge of said outer sides 65 is a guard flange 17. Formed integrally with the top side of the body 1 and located adjacent the strip 11, are upstanding tread receiving ribs 18 and 19, which extend from the ends of said body, conform to the gradually upwardly inclined surfaces 8 and 9, and curve downwardly at 20 and 21 until they merge into said body short of its transverse center. The top surfaces of the ribs 70 18 and 19, indicated by 22 and 23 respectively, are adapted to receive the tread of a car wheel and thus relieve the flange thereof of supporting the weight.

The outside replacer 3 consists of an elongated body of greater width at its ends than 85 at its transverse center, and having a base 24 for resting upon the cross-ties 5, which base is inclined at 25 for resting upon the top side of the base of the rail. The elongated body of this replacer has gradually 90 upwardly inclined upper surfaces 26 and 27 extending from each end thereof and rounding into a horizontal ledge 28, which is adapted to engage the side of the head of the rail. Facing lugs 29 and 30 are provided at the inner side of the ledge 28 and at the ends thereof for engaging the web of the rail. Formed integrally with the upper surfaces 26 and 27 and the ledge 28 of 95 the body of the outer replacer 3, is a raised central portion 31 which is curved gradually from each end from said surfaces to its highest point 32, and the inner side thereof is convex at 33 and rounds into said ledge at 34. The inner side of the raised central 100 portion 31 is depressed or concave at its center down to the ledge 28 as at 35. A guard flange 36 is formed integrally with the upwardly inclined upper surfaces 26 and 27 at the inner edge of the body, and 105 110

its upper surfaces, indicated by 37, gradually curve from the ends into the top surface of the raised central portion 31. Said upper surfaces of the guard flanges are 5 adapted to receive the tread of a car wheel.

It will be understood that each of the elongated bodies of the car replacers 1 and 3 may be hollowed out and provided with 10 suitable ribs as shown at 38 to make them light and at the same time of sufficient strength to carry great weight to which such devices are subjected. Each car replacer is easily and quickly secured to a rail by the following described means:

15 An opening as 39 is provided in the outer side of the body of the car replacer for receiving the sleeve end 40 of a nut 41 formed integrally with a hand-wheel 42, which nut is mounted upon an elevated threaded shank 20 43 of a member 44 terminating in a hook 45 for engaging the flange of the rail. The member 44 is inclined downwardly from said shank at 46, and then upwardly to the hook 45 at 47, so as to clear the base of the 25 rail when the nut 41 is being turned up to draw the car replacer to the rail.

In practice, the car replacers are arranged along and attached to the rails in any suitable position for receiving the derailed 30 wheels of a car. Assuming that the car is being pulled to the left, the flange of one wheel will travel upon the inclined surface 8 of the inside replacer 1, and the tread thereof will soon, if not at once, travel upon 35 the top surface 22 of the rib 8, and as it leaves the end 20 thereof, the flange of the wheel will engage the convex surface 15 and thus the car wheel will be gradually forced laterally upon the rail 2. At the same time, 40 the flange of the opposite car wheel will travel upon the inclined surface 26 of the outside replacer 3, and the tread thereof upon the top surface 37, and as the flange and tread of a car wheel come in contact 45 with the raised central portion 31, the car wheel will be forced laterally, and its flange will engage the depression or concave center surface 35 and then the ledge 28, and pass over the rail 4 until the tread of the car 50 wheel rests upon the same.

Although the car replacers illustrated and described will accomplish the purpose for which they are intended, it will be understood that slight modifications in the design 55 may be made within the scope of the claims.

Having fully described my invention, what I claim is:

1. In a car replacer, an elongated body, the body having upwardly inclined surfaces extending from each end thereof, a guard flange projecting upwardly from said inclined surfaces of the body at the outer side thereof and inclined inwardly from the ends of the body, a longitudinal strip at the inner side of the body adapted to engage the web

of the rail, the body having a convex surface extending from the longitudinal strip to its inclined surfaces, tread receiving ribs standing upwardly from said inclined surfaces of the body adjacent said longitudinal 70 strip and extending from the ends of the body, and the tread receiving ribs terminating short of the transverse center of the body and being curved downwardly and merging into said convex surface of the body, substantially as described. 75

2. In a car replacer, an elongated body, the body having upwardly inclined surfaces extending from each end thereof, the body having a horizontal ledge at its inner side, the upwardly inclined surfaces of the body rounding into the ledge, the inner side of said ledge being adapted to engage the head of a rail, lugs at said inner side of said ledge adapted to engage the web of a rail, the body having a raised elongated central portion projecting from the inclined surfaces thereof and being adjacent said ledge, the side of said raised central portion next to the ledge being convex and rounding thereinto, the ends of the raised central portion being convex and rounding into said inclined surfaces of the body, said raised central portion being concave at its center on the side adjacent said ledge, tread receiving flanges projecting upwardly from said inclined surfaces of the body at the outer side thereof and inclined inwardly and upwardly from the ends of the body, and said tread receiving flanges merging into said raised central portion, substantially as described. 90

3. In a car replacer, an inside elongated body and an outside elongated body, each body having upwardly inclined surfaces extending from the ends thereof, a guard flange 105 projecting upwardly from the inclined surfaces of the inside body at the outer side thereof and inclined inwardly from the ends of the body, a longitudinal strip at the inner side of the inside body adapted to engage the web of a rail, the inside body having a convex surface extending from the longitudinal strip to its inclined surfaces, tread receiving ribs standing upwardly from said inclined surfaces of the inside body adjacent 110 said longitudinal strip and extending from the ends of the inside body, the tread receiving ribs terminating short of the transverse center of the inside body and being curved downwardly and merging into said convex 115 surface of the inside body, the outside body having a horizontal ledge, the upwardly inclined surfaces of the outside body rounding into said ledge, the inner side of said ledge

being adapted to engage the head of a rail, the outer body having a raised elongated central portion upwardly from the inclined surfaces thereof and being adjacent said ledge, the side of said raised central portion next to the ledge being convex and rounding 120 125 130

thereinto, the ends of the raised central portion being convex and rounding into said inclined surfaces of the outer body, said raised central portion being concave at its center
5 on the side adjacent the horizontal ledge, tread receiving flanges projecting upwardly from said inclined surfaces of the outer body

at the outer side thereof and inclined inwardly and upwardly from the ends of said body, and said tread receiving flanges merging into said raised central portion, substantially as described.

In testimony whereof I affix my signature.
HERMAN SABROWSKE.
